UNITED STATES PATENT OFFICE.

ADOLF SCHWIEGER, OF HANOVER, GERMANY.

LOCK.

1,071,266.

Specification of Letters Patent.

Patented Aug. 26, 1913.

Application filed March 29, 1911. Serial No. 617,558.

To all whom it may concern:

Be it known that I, ADOLF SCHWIEGER, a subject of the German Emperor, residing at Hanover, in Germany, have invented a certain new and useful Improvement in Locks, of which the following is a specification.

This invention relates to locks having means for dogging the protracted bolts (latch bolt and dead bolt) by actuation of the handle.

The object of the present invention is to provide a lock of this kind, wherein said dogging means also comprises a device for shooting the dead bolt, so that the entire operation of locking can be effected by means of the handle, without using a key.

The invention is illustrated in the accompanying drawing, in which:—

20 Figure 1 is an elevation showing the interior of the lock, with the latch bolt free and the dead bolt retracted, the retracted position of the latch bolt being indicated by dotted lines. Fig. 2 is an elevation showing the latch bolt dogged and the dead bolt free to be shot by the handle-actuated mechanism, the shot position of the dead bolt being indicated by dotted lines. Fig. 3 is an elevation viewed at right angles to the 30 plane of Fig. 1.

In the drawing, *a* represents the lock-case, *b* the latch bolt, and *c* the dead bolt. The latch bolt is actuatable by the spindle roll-back *d*, which is also adapted to actuate the dead bolt by means of the lever *e*. The dead bolt is actuatable in the usual manner by means of a key, and is locked by the tumbler *f*. *g* is a vertically movable slide adapted to be actuated by the spindle roll-back 40 and to dog both bolts. The spindle roll-back *d* has notches *h* for engagement with the handle-lever *d'* indicated in Fig. 3 by dotted lines. On depression of the handle-lever *d'* the arm *i* on the spindle roll-back 45 co-acts with the pendent portion *k* of the latch bolt and retracts the latter as indicated by dotted lines in Fig. 1. When the handle is released the latch bolt is shot by the spring *z*. To lock the latch-bolt in its 50 shot position the handle is lifted to rotate the spindle roll-back into the position shown in solid lines in Fig. 2. The arm *m* on the spindle roll-back is thus caused to lift the slide *g* so that the upper end of the latter 55 moves behind the shot latch bolt and prevents retraction of this bolt. In this position

the notched arm *i* is engaged by the spring *o*. The slide *g* is engaged with the tumbler *f*, and by its upward movement lifts the tumbler out of engagement with the retracted dead bolt. By further rotation of the handle in the same direction the arms *m* and *i* are moved to the position indicated by dotted lines in Fig. 2. The arm *i*, acting on the arm *p* of lever *e*, causes the arm *r* 60 of the latter to thrust forward the upward projection *s* of the dead-bolt, and shoot said bolt, against the action of spring *t*, the positions of the slide, lever *e*, tumbler and dead-bolt being indicated by dotted lines in Fig. 2. 65 When the parts are in these positions, a lateral portion *w* of the lower end of the slide *g* projects behind the shot dead bolt and prevents retraction of same. The arm *i* is held by the spring *o* engaging over its upper 70 edge, and the tail of said spring *o*, abutting against the lever *e*, is bent as indicated by dotted lines. On rotation of the lifted handle lever in the opposite direction the slide *g* is first removed from behind the dead bolt 75 *c*, and this bolt is retracted by spring *t*. Then the slide *g* is also withdrawn from behind the latch bolt *b*. The lever *e* is restored to normal position by the spring *o*. Toothed gear wheels or equivalent means 80 may be used instead of a lever arm, for imparting movement to the locking slide *g* by means of the handle spindle.

What I claim as my invention and desire to secure by Letters Patent of the United 90 States is:—

1. In a lock the combination of a latch bolt, a dead bolt, a handle-spindle roll-back, a locking member movable by said spindle roll-back constructed to first lock the latch 95 bolt and then lock the dead bolt, and a device actuatable by said spindle for shooting the dead bolt between the said operations of the locking member.

2. In a lock the combination of a latch 100 bolt, a dead bolt, a handle-spindle roll-back, a dogging member movable by said spindle constructed to first dog the latch bolt and then dog the dead bolt, a device actuatable by said spindle roll-back for shooting the 105 dead bolt during the movement of the dogging-member and after the latch-bolt is dogged, and a tumbler which normally locks said dead bolt and is engaged with said dogging member so that said tumbler is disengaged from said dead bolt by the movement 110 of said dogging member.

3. In a lock the combination of a latch bolt, a dead bolt, a handle-spindle roll-back, a slide movable into the inward paths of the shot bolts, means operatively connecting said slide to said spindle roll-back, and a device actuatable by the spindle roll-back for shooting the dead bolt prior to movement of the slide into the path of the dead bolt.
4. In a lock the combination of a latch bolt, a dead bolt, a handle spindle roll-back, a slide movable into the inward paths of the shot bolts, means operatively connecting said slide to said spindle roll-back, an arm on said spindle roll-back for retracting the latch bolt, and a lever actuatable by the latch-retracting arm for shooting the dead bolt prior to movement of the slide into the path of the dead bolt.
5. In a lock the combination of a latch bolt, a dead bolt, a handle spindle roll-back, a locking member movable by said spindle roll-back constructed to first lock the latch bolt and then lock the dead bolt, a device actuatable by said spindle roll-back for shooting the dead bolt between the said consecutive operations of the locking member, and means for retaining the spindle roll-back in a position which it occupies between the locking of the latch bolt and the shooting of the dead bolt.

In witness whereof I have signed this specification in the presence of two witnesses.

ADOLF SCHWIEGER.
